UNITED STATES PATENT OFFICE.

GEORGE W. JOHNSON, OF OAKLAND, CALIFORNIA.

CAN-OPENER.

1,080,636.

Specification of Letters Patent.

Patented Dec. 9, 1913.

Application filed October 31, 1912. Serial No. 728,876.

To all whom it may concern:

Be it known that I, GEORGE WALTER JOHNSON, a citizen of the United States, residing at Oakland, in the county of Alameda and State of California, have invented certain new and useful Improvements in Can-Openers, of which the following is a specification.

My invention is in the nature of a machine for opening cans of hermetically-sealed goods, such as fruits, oysters, and vegetables, by cutting out the top of the can close to the securing bead thereof.

The object of my invention is to provide such a device which is adaptable for use with cans of various heights and diameters, which will quickly and accurately cut out the head of a can, close to the edge thereof, so that the entire contents may be quickly 20 and completely removed from the can, and one which will cut the head from the can in such fashion as to force the metal remaining secured to the upper edge of the can body downwardly in contact with the 25 inner face of the can body.

My invention consists in a turret head rotatably mounted on a supporting frame and provided with a plurality of circular cutting members of different diameters, a 30 seat for receiving and engaging the lower end of the can to be cut, means for raising the can contained in its seat toward the cutting edge, and means for removing the can from the cutting edge after the can head 35 has been severed from the body.

With the above mentioned and other objects in view, the invention consists in the novel construction and combination of parts hereinafter more fully described, illustrated 40 in the accompanying drawings and pointed out in the claims hereto appended.

Reference now being had to the accompanying drawings, wherein is disclosed one form of my invention and in which—

Figure 1 is a front elevation of my invention partly in section, disclosing the turret head, the can seat and the operating means therefor. Fig. 2 is a vertical sectional view disclosing the construction of the turret head and the manner of mounting the knives therein, and the can seat and the manner of raising and lowering the same. Fig. 3 is a detail of a supplementary can seat adapted for use in connection with short cans.

Referring more particularly to the draw-

ings, the reference numeral 1 designates a suitable base provided with a central bore 2, and upwardly extending parallel spaced supporting arms 3, in the upper ends of which are mounted a horizontally extending shaft 4, which supports a hollow turret head 5 rotatably mounted thereon between the upper ends of said arms 3. The turret head 5 is substantially rectangular in form and in the faces thereof are formed suitable cylindrical openings 6, each of a different diameter, and said openings communicate with the interior of the turret head. Surrounding each opening is an annular flange 7 at the lower edge of which is provided an annular seat 8.

9 designates the head cutting knives, each of which consists of a strip of steel provided with saw like teeth 10 and 11, the teeth 11 being slightly longer than the teeth 10, and said strips of steel are bent into circular form, and are inserted in the openings 6 with the lower edges thereof resting on the seats 8, the knives being retained in position by the frictional securing rings 12, 80 and each knife is of a diameter equal to the inside diameter of a standard size can.

Mounted to reciprocate in the central bore 2 is a plunger 13 carrying at its upper end a semi-circular flanged portion 14, provided 85 on its inner surface with semi-circular seats 15 of different diameters, each of which is provided with an overhanging flange 16 and said seats are of a diameter corresponding to the diameter of certain of said knives 9, 90 and it will be observed that when a can is positioned within one of said seats that the overhanging flange 16 thereof will engage over the bottom end seam 17 of the can and retain the same in position. 95

The lower end of the plunger 13 is recessed, providing a flat seat 18 which rests on a corresponding flat seat 19 formed on the inner end of an oscillating shaft 20, mounted in a cylindrical bore 21, formed in the base 1 and communicating with the bore 2, the outer end of said shaft being provided with an arm 22 terminating at its upper end in a handle 23, the shaft 20 being retained in position by a set screw 24 which projects through an elongated opening 25 in the shaft 20. A semi-circular recess 26 is formed in the lower portion of the plunger 13 adjacent the seat 19, and in said recess is adapted to operate a lug 27 projecting 110

from the end of the shaft 20 and said lug engages the edge of said recess.

From the above construction it will be observed that by the operator swinging the handle 23 in the direction of the arrow—
5 Fig. 1, the rear edge A of the flat face 19 will be forced upwardly, raising the plunger 13 carrying a can, and the lug 27 will ride on the edge of the semi-circular cut-out 26, and as the movement of the lever 22 is reversed, the lug 27 will frictionally engage the edge of the cut-out 26 and will draw the plunger 13 downwardly, thus there is provided a double cam movement, one raising 10 the plunger and the other drawing the same downwardly.

The annular flanges 7 are provided on their peripheral edges with suitable guide fingers 28 which properly present the upper 20 end of the can to the knife 9. The turret is locked from movement relative to the shaft 4 with one of the knives 9 in proper cutting relation to the can head, by a locking pin 29 slidably mounted in a suitable 25 bore in the upper end of one of the supporting arms 3, and the inner end of said pin is adapted to be inserted in recesses 30 formed in the turret and each of said recesses being so positioned as to properly 30 position one of said cutting knives relative to the can head when the end of the pin is inserted in the recess.

The plunger 13 is provided in its center with a recess 31 open at the upper end thereof and said recess is adapted to receive a stem of a can seat, disclosed in full lines—
35 Fig. 3, and said supplementary can seat is employed only with short bodied cans, to properly position the top thereof relative to 40 one of said cutting knives.

In operation, the turret is rotated to properly position the knife, corresponding in diameter to the can head to be severed, the lower end of the can is inserted in its proper 45 sized seat with the flange associated therewith overhanging the bottom flange of the can, the lever 22 is moved in the direction of the arrow which through its associated parts will raise the can, and the top thereof 50 will be engaged first by the cutting teeth 11 and after the points thereof have penetrated the can top, the points of the teeth 10 will engage and penetrate the top, and as the can is forced upwardly the entire top thereof will be severed from the body close to the inner surface of said body. The can now having reached its highest point of movement, the head being severed therefrom and the top of the can body being in close relation to the end of the flange 7, the direction 55 of movement of the lever is reversed and the lug 27 riding in the cam slot 26 will draw the can seat downwardly and the can being engaged thereby will also be drawn down-

wardly and the upper end thereof will be 65 disengaged from the cutting knife.

It will be observed that I have provided a device which is capable of quickly and accurately cutting the heads from cans of different diameters and heights, is simple and inexpensive in construction, and is thoroughly efficient in all of its operations.

Having thus described my invention what is claimed as new and is desired to be protected by Letters Patent is—
75

1. In a can opener, the combination with a frame provided with a pair of spaced vertically extending arms, a movable can support carried by said frame and provided with can seats of different diameters for the reception of the cans to be opened, a turret head rotatably carried between the upper ends of said arms, circular cutting knives of different diameters secured to said head and adapted for severing the head 85 from a can adjacent its peripheral edge, means for retaining one of said knives in operative position to the can head to be severed, and an operating lever for moving said can support toward and from said turret head to force the cutting knife carried by the turret head into the can adjacent its peripheral edges and completely sever the same from its body.

2. In a can opener, the combination with 95 a frame provided with a pair of parallel spaced vertically extending arms, a vertical movable can support carried by said frame between the lower ends of said arms, a plurality of can seats of different diameters 100 formed in said base and each provided with an overhanging flange for engagement with the bottom flange of the can to be opened, a turret head rotatably carried between the upper ends of said arms, circular cutting 105 knives of different diameters secured to said head and adapted for severing the head from the can adjacent its peripheral edge, means for retaining one of said knives in operative relation to the can head to be 110 severed, a lever actuated cam for raising said can support to force the top of the can carried thereby into contact with one of said cutting knives, said knife completely severing the head from its body adjacent 115 the peripheral edge thereof, and an independent cam controlled by said lever for lowering the can support to withdraw the can body from contact with said knife after the top has been severed therefrom.

3. In a can opener, the combination with 120 a frame provided with a pair of spaced vertically extending arms, a can support carried by said frame at the lower ends of said arms and provided with a plurality of semi-circular can seats of different diameters for the reception of cans to be opened, an overhanging flange associated with each of said 125

can seats for engaging the bottom flange of a can to be opened, a turret head rotatably carried between the upper ends of said arms, circular cutting knives each of a different 5 diameter detachably secured to said head and adapted for severing the head from a can adjacent its peripheral edge, a pin associated with one of said arms and adapted to engage said turret head for retaining one 10 of said knives in operative relation to the can head to be severed, and an operating

handle for raising and lowering said can support relative to said positioned cutting knife.

In testimony whereof I have signed my ¹⁵ name to this specification in the presence of two subscribing witnesses.

GEORGE W. JOHNSON.
